CLAIM

The ornamental design for a combined desk set, pen holder and thermometer, as shown and described.

DESCRIPTION

FIG. 1 is a perspective view of a combined desk set, pen holder and thermometer showing my new design with the tray cover in an open position,

FIG. 2 is a front elevational view thereof with the tray cover closed,

FIG. 3 is a right end elevational view,

FIG. 4 is a left end elevational view,

FIG. 5 is a top plan view,

FIG. 6 is a rear elevational view; and

FIG. 7 is a bottom plan view.

The indicia shown on the thermometer in FIGS. 1 and 5 is for illustrative purposes only.
